UNITED STATES PATENT OFFICE.

ALBERT E. BATES, OF NYACK, NEW YORK

FILING-CASE.

1,184,709.

Specification of Letters Patent.

Patented May 30, 1916.

Application filed September 17, 1915. Serial No. 51,160.

To all whom it may concern:

Be it known that I, ALBERT E. BATES, a citizen of Canada, residing in the city of Nyack, Rockland county, State of New York, have invented or discovered certain new and useful Improvements in Filing-Cases, of which the following is a full, clear, and complete disclosure.

My invention relates to improvements in filing cases such, for example, as are used for retaining bank statements, or other papers or documents which it is necessary to consult or examine at frequent intervals.

An object of my invention is to provide a filing case which when open, will retain the contents in such a position that they are easily accessible, and when closed, will provide a dust-proof receptacle convenient for filing.

Another object of my invention is the provision, in combination with my improved filing case, of a stand or support therefor, which stand is so constructed as to retain the case when open, in such a position that the contents thereof may be readily consulted or manipulated.

Other objects of my invention will appear from the specification and claims which follow.

Referring to the drawing: Figure 1 is a perspective view of my improved case, shown in open position resting upon its stand or support, and Fig. 2 is a perspective view of the case in closed position.

The case or box A comprises two sections B and C which are hingedly connected together at 10, as shown. The section B, preferably includes the wall 11, which serves as the bottom of the box when closed, the adjacent wall 12, and the cover 13 hinged to the top of the side wall 12. Connected to the bottom and side walls 11, 12, are the end walls 14, 15, one or both of which may be partially cut away to facilitate access to the contents of the box.

The section C includes the side wall 16, which, as above indicated, is hingedly connected at 10 to the bottom wall 11 of section B, the top wall 17, and the end walls 18, 19. The top wall 17 is preferably cut away as indicated in the drawing and the side wall 16 is preferably provided at its upper edge with a recess, such as 20, whereby the manipulation of the sheets of paper, or other contents of the box when resting on the side

wall 16 is facilitated, as will be readily understood.

In order to retain the box in the most convenient position, when open, I have devised a stand or base D, which may either be adapted to rest upon a table or may be supplied with suitable supporting legs, the object being to provide a stand which may be conveniently placed in any desired position. This stand D is preferably provided with a longitudinally extending V-shaped recess 21 within which the bottom wall 11 and the lower portion of the side wall 12 of section B are adapted to rest, so that the walls 11 and 12 are retained in oppositely inclined positions. The side wall 16, of section C, rests on the flat portion of the support and is thus retained in a substantially horizontal position.

The method of using my invention is as follows: Assuming that it is desired to consult, examine or copy the cards, papers, or other contents of one of the boxes A, this box is opened and placed on a stand D located in a convenient point as, for example, adjacent a typewriter stand. The papers or cards to be examined are supported at their lower edges by the wall 11 and rest face up against the wall 12. By reason of this inclined position of the cards or sheets, it is very easy to examine them one by one, or to copy their contents, and then deposit them face downward upon the wall 16. After all of the cards or sheets have been examined, they are all lying face downward on the wall 12, so that the box may easily be closed and filed away. Any suitable latching and locking means such as indicated at 22, may be employed for retaining the box closed.

While I have illustrated but one embodiment of my invention, it is to be understood that I do not wish to limit myself to this particular form of device, since, obviously, many changes may be made therein without departing from the spirit of my invention.

What I claim is:

1. A filing case comprising a pair of sections, one of said sections including a bottom wall, a side wall, a pair of end walls, and a hinged cover, and the other of said sections including a side wall, hingedly connected to the bottom wall of the first mentioned section, a top wall and a pair of end walls, one of the end walls of the first

mentioned section and the top wall of the last mentioned section being partially cut away to permit easy access to the contents of the case when open.

zontal base provided with a longitudinally extending V-shaped recess, and a filing case adapted to be supported by said base, said case comprising a pair of sections, one of said sections including a bottom wall, a side wall, a pair of end walls, and a hinged cover, and adapted to rest in said V-shaped recess so that the bottom and side walls are retained in oppositely inclined positions, and the other of said sections including a side wall hingedly connected to the bottom wall of the first mentioned section and adapted to rest in substantially horizontal position on said base, a top wall and a pair of end walls.

6. In combination, a substantially horizontal base provided with a longitudinally extending V-shaped recess, and a filing case adapted to be supported by said base, said case comprising a pair of sections, one of said sections including a bottom wall, a side wall, a pair of end walls, and a hinged cover, and adapted to rest in said V-shaped recess so that the bottom and side walls are retained in oppositely inclined positions, and the other of said sections including a side wall hingedly connected to the bottom wall of the first mentioned section and adapted to rest in substantially horizontal position on said base, a top wall and a pair of end walls, one of the end walls of the first mentioned section and the top wall of the last mentioned section being partially cut away to permit easy access to the contents of the case.

In testimony whereof I have signed this specification in the presence of two subscribing witnesses.

ALBERT E. BATES.
